ABSTRACT: An electrohydraulic metal-forming machine which is capable of simultaneously forming a plurality of sheet-metal or tubular workpieces into the same or different shapes or configurations by electric discharge. The machine comprises a discharge chamber to be filled with a liquid and a pair of electrodes having a gap disposed in the discharge chamber. A plurality of dies of the same or different shapes or configurations are arranged either radially about the discharge chamber in liquid communicating relation thereto or in such a manner that the working surfaces of the dies constitute part of the inner surface of the discharge chamber. A workpiece is put in or applied against each of the dies so that electric discharge causes an impulsive pressure to be generated in the liquid to deform all the workpieces simultaneously to conform to the shape or shapes of the dies.

SHEET 2 OF 2

ELECTROHYDRAULIC METAL-FORMING MACHINE

This invention relates to an electrohydraulic metal-forming machine for forming sheet-metal or tubular workpieces into desired shapes or configurations.

In conventional electrohydraulic metal-forming machines which deal with sheet-metal workpieces, the arrangement is generally such that a sheet of metal to be formed is applied to the working surface of a die, which is placed upside down or sideways toward an electric discharge chamber filled with a liquid, so that the impulsive pressure generated in the liquid by discharge is utilized to deform the sheet into the shape or configuration as defined by the die. With such conventional machines, however, a single shot of electric discharge can produce only a single product. If the desired final shape is complicated, the forming process must be carried out in several steps to gradually approach the final shape, because if the process were carried out by a single shot, the impulsive pressure would be so concentrated on particular points of the workpiece that it would suffer an abnormal internal stress and be ruptured or broken down. For mass production of such parts of complicated shapes, therefore, there must be provided as many separate machines having differently shaped dies as there are steps of the forming process, each of the machines taking care of only one of the steps, with a resulting increase in the cost of equipment and personnel expenditure.

In conventional electrohydraulic metal-forming machines which deal with tubular workpieces, the arrangement is generally such that a pair of electrodes are inserted into the opposite openings of a tubular workpiece. This arrangement, however, has serious defects such as follows: First, one of the electrodes requires up-and-down movement and the gap therebetween, readjustment upon every feeding and unloading of a workpiece into and out of the machine, and with a single shot of discharge it is possible to obtain only a single product. This is certainly time consuming and quite inefficient. Secondly, the size of the electrodes is restricted by the size of the tubular workpiece. In the case of a thin tube, for example, the electrodes must be correspondingly small and thin, with a resulting decrease in their mechanical strength and shortening of their life. Moreover, the space between each electrode and the inner surface of the tubular workpiece becomes narrow. This will cause damage to the inner surface of the workpiece due to the electric discharge between the electrodes and the workpiece instead of between the two electrodes alone as in normal discharge. Also, because of the narrow space between the electrodes and the inner surface of the tube, only a small quantity of liquid can fill the space, with a resulting pressure drop in the liquid as it goes away from near the electrode tips. This will cause partial bulging of the tube adjacent the electrode tips only, and the longer is the tube, the greater will be this tendency of partial bulging.

The primary object of the invention is therefore to provide an electrohydraulic metal-forming machine which is completely free of the above and other defects of the conventional types.

Another object of the invention is to provide an electrohydraulic metal-forming machine which is capable of simultaneously forming a plurality of workpieces into the same desired single shapes or configurations.

Another object of the invention is to provide an electrohydraulic metal-forming machine which is capable of simultaneously forming a plurality of workpieces into different shapes or configurations.

In one embodiment of the invention, the machine comprises a discharge chamber adapted to be filled with a suitable liquid, a pair of electrodes having a gap disposed in said chamber, a plurality of dies arranged radially about said discharge chamber in liquid communicating relation thereto and comprising two separable die sections adapted to enclose a workpiece therein so that the workpiece may contact the liquid at its one surface and faces the die at its opposite surface, and means for supplying electric energy to said electrodes to cause a spark discharge to occur between said electrodes.

In another embodiment of the invention, the machine comprises a discharge chamber adapted to be filled with a suitable liquid, a pair of electrodes having a gap disposed in said discharge chamber, a plurality of movable dies the working surfaces of which constitute at least part of the inner surface of said chamber and are adapted to receive a workpiece thereon so that said workpiece may contact said liquid at its one surface and is supplied at its opposite surface against the working surface of each said die, and means for supplying electric energy to said electrodes to cause a spark discharge to occur between said electrode.

The invention will be made clear by the following description with reference to the accompanying drawings in which:

FIG. 1 is a schematic elevational view, in vertical section, of one embodiment of the invention;

FIG. 2 is an elevational view, partly in vertical section, of a finished product obtained by the operation of the machine of FIG. 1.

FIG. 3 is a view similar to FIG. 1, but showing another embodiment of the invention;

FIG. 4 is a transverse section taken along the line A—A of FIG. 3;

FIG. 5 is an elevational view, partly vertical section, of a finished product obtained by the operation of the machine of FIGS. 3 and 4;

FIG. 6 is a view similar to FIGS. 1 and 3, but showing a third embodiment of the invention;

FIG. 7 is a transverse section taken along the line B—B of FIG. 6; and

FIG. 8 is a perspective view of a finished product obtained by the operation of the machine of FIGS. 6 and 7.

Referring to FIG. 1, there is shown a housing 11 which defines the lateral sides of a discharge chamber 12 while leaving the top and bottom sides thereof open. The housing 11 is rigidly supported by a machine frame 13. A pair of electrodes 14 and 14' are inserted through the opposite sidewalls of the housing into the discharge chamber 12 so that they face each other across a gap 15. To the electrodes there is connected an energizing circuit 16 including a switch 17 and a condenser 18 charged from a suitable source through a transformer 19 and a rectifier 20.

A pair of upper and lower dies 21 and 22 are fixed to a pair of die plates 23 and 24, respectively, each of which is in turn fixed to a driving rod 25, 26 of a suitable oil-pressure-operated clamping device, not shown. Thus, the dies 21 and 22 are movable relative to the housing 11 so as to close and open the discharge chamber 12. When the dies tightly close the chamber with their respective working surfaces facing inwardly toward the chamber, a suitable liquid 27 is introduced through a passage 33 to fill the discharge chamber 12, so that an impulsive pressure may be generated in the liquid in the manner to be described later. The dies 21 and 22 have die cavities 28 and 29 formed on their respective working surfaces. The shapes of the dies are different from each other and those required at different successive steps of a desired forming process. That is, the shape of the upper die cavity 28 is that into which a workpiece is first shaped at the first step of the forming process and the shape of the lower die cavity 29 is that into which that workpiece that is through the first step is shaped at the next step to attain the required final shape. The lower die cavity 29 is provided with a central projection 29' corresponding to the upper die cavity 28. A sealing member

55 60 65 70 75

30 tightly seals between the dies 21, 22 and the housing 11 against any leakage of the liquid 27 from the chamber 12.

In operation, a workpiece 31a in the form of sheet metal is held between the upper die 21 clamped into the chamber closing position as shown in FIG. 1 and the upper shoulder 32 of the housing 11 so that one surface of the workpiece 30 is applied against the working surface of the upper die 21, and with the lower die 22 having been clamped into the chamber closing position, liquid 27 is introduced into the discharge chamber, whereupon the opposite surface of the workpiece is 75 in contact with the liquid filling the discharge chamber. As the

liquid fills the chamber, the air therein is pushed out therefrom through a passage 33'. Under the condition, when the switch 17 is closed, a discharge takes place across the gap 15 between the electrodes 14 and 14' and causes an impulsive pressure to be generated in the liquid 27. This pressure deforms the workpiece 31a to conform to the shape or configuration of the working surface of the upper die 21. That is, the portion of the workpiece which corresponds to the upper die cavity 28 is depressed thereinto to conform to the shape thereof, so that a depression or projection 31' is formed in the workpiece. Evacuation of the die cavity 28 through a passage 34 prevents the air in the cavity from restricting the proper deformation of the sheet metal 33.

When the first shot of discharge has been completed, the liquid 27 is withdrawn from inside the discharge chamber through the passage 33, and the dies 21 and 22 are moved away from the housing 11 to remove the workpiece from the upper die 21. Then, this workpiece 31a is held between the lower die 22 clamped into place and the lower shoulder 32' of the housing 11, and a new workpiece 31b is held between the upper die clamped into place and the upper shoulder 32 of the housing 11. After that, the liquid is again introduced into the discharge chamber to fill the same, and a discharge is again caused to occur in the manner previously described. As a result of this second shot of discharge, the upper workpiece 31b is deformed just in the above-mentioned manner, and the lower workpiece 31a is deformed to conform to the lower die cavity 29, with the projection 29' thereof fitting into the depression 31' already formed in the workpiece 31a at the preceding step of the forming process. A pair of passages 34 are provided to evacuate the lower cavity 29 for the same purpose of the above-mentioned relief passage 34.

After the second shot of discharge, the liquid in the chamber is withdrawn and the two dies are removed from the housing 11. The finished article taken out of the lower die is shown in FIG. 2.

The structure of FIG. 1 is designed to perform two different shapes of a forming process simultaneously, that is, by a single shot of electric discharge. If the forming process requires more than two steps, the corresponding number of dies must be provided. FIGS. 3 and 4 show an arrangement suitable for performing the four different steps of a forming process at the same time.

A housing 35 supported by a base 36 defines a discharge chamber 37 therein and has four windows 35a, 35b, 35c and 35d. A pair of electrodes 38 and 38' are inserted through the top and bottom walls 35' and 35'' of the housing 35 into the chamber 37 so that they are juxtaposed across a gap 39. To the electrodes there is connected an energizing circuit 40 similar to the circuit 16 in FIG. 1 including a switch 41 and a condenser 42 charged from a suitable source through a transformer 43 and a rectifier 44.

Four different dies 45, 46, 47 and 48 carried by die plates 49, 50, 51 and 52, respectively, are movable relative to the housing 35 to open and close the windows 35a, 35b, 35c and 35d of the housing 35 by means of rods 53, 54, 55 and 56, respectively, each of which is driven by a suitable oil-pressure-operated clamping device, not shown.

When the four dies tightly close the discharge chamber 37 with their respective working surfaces facing inwardly toward the chamber, suitable liquid 57 is introduced into the chamber through a passage 64 to fill the chamber. The dies 45-48 have formed on their respective working surfaces die cavities 58, 59, 60 and 61, the shapes or configurations of which are those required at the four different steps of a required forming process. Sealing members 62 tightly seal between the housing walls and surfaces of the workpieces applied against the dies, so that the liquid in the chamber 37 may not enter the die cavities.

In operation, a workpiece 63a in the form of a sheet of metal is applied against the die 45, and after the first shot of discharge, it is removed from the first die 45, with a depression 63' formed thereon, onto the second die 46. At the same time,

5 a new sheet of metal 63b is held against the first die 45, and after the second shot of discharge, the first workpiece 63a has a configuration 63'' formed thereon and is removed from the second die 46 onto the third die 47. At the same time the second workpiece 63b is transferred from the first die 45 onto the second 46, with a new workpiece 63c being placed on the first die 45. Then after the third shot of discharge, the first workpiece 63a has a configuration 63''' formed thereon and is transferred from the third die 47 onto the fourth die 48. At the same time, the second and third workpieces 63b and 63c are transferred from the second and first dies 46 and 45 onto the third and second dies 47 and 46, respectively, and a fourth workpiece 63d is placed on the first die 45. Then, after the 10 fourth shot of discharge, the first workpiece 63a has been formed into the final desired shape as shown in FIG. 5. It will be easily seen that from the next shot of discharge every single 15 shot of discharge can effect simultaneous deformation of four workpieces into four different shapes. Relief passages 85 are 20 provided for evacuation of the die cavities just as in the arrangement of FIG. 1.

FIGS. 6 and 8 show a third embodiment of the invention 25 designed for forming a plurality of tubular workpieces into the same shape simultaneously. There are shown a pair of upper and lower die sections 65 and 66. The lower die sections 66 is rigidly supported by a base 67, while the upper die section 65 is fixed to a die plate 68 and vertically movable relative to the lower die section 66 by means of rods 69 driven by a suitable oil-pressure-operated clamping device, not shown. When put together, the two die sections define a central discharge 30 chamber 70 and four die cavities 71 of the same shape or configuration. The four dies are arranged radially about the discharge chamber 70 in liquid communicating relation thereto. A pair of electrodes 72 and 72' are inserted through the upper and lower die sections into the discharge chamber 70 so as to face each other across a gap 74. The electrodes are 35 connected to an energizing circuit 75 including a switch 76 and a condenser 77 charged from a suitable source through a transformer 78 and a rectifier 79.

In operation, a workpiece 80 in the form of a tube is placed 40 in each of the four dies, with a stopper 81 fitted into the outer end opening of the tube. A suitable liquid 82 is introduced into the chamber 70 through a passage 83 in the lower die section 45 to fill the chamber and also the four tubular workpieces 80. As the liquid fills the chamber and the workpieces 80, the air 50 therein is pushed out through a relief passage 83' in the upper die section. Sealing rings 84 prevent the liquid from entering between the inner surface of each die and the outer surface of the tube. Relief passages 86 are provided for the same purpose as in the previous arrangements.

When the switch 76 is closed, an electric discharge taking 55 place between the electrodes causes an impulsive pressure to be generated in the liquid 82. This pressure deforms the tubular workpieces to conform to the same shape of the four dies. The final shape of the workpieces is shown in FIG. 8. It is seen that the machine of FIGS. 6 and 7 is capable of dealing with four workpieces at the same time. Needless to say, the number 60 of dies provided may be increased or decreased as occasions demand. Such modified forms with more or less dies will be so apparent to those who have read the specification that no illustration or explanation will be necessary.

In the illustrated embodiments of FIGS. 1, 3 and 4, the 65 shapes of the dies are mutually related, that is, those shapes into which the workpiece is formed at different succeeding steps of a required forming process directed to a single final shape. If desired, the dies may have different independent shapes having no mutual relation. Also in FIGS. 6 and 7 the 70 dies are of the same shape, but they may have different shapes, whether mutually related or not.

If the workpiece is so thick or of so rigid a material that a single shot of discharge may not sufficiently deform it, a plurality of shots may be conducted to deform the workpiece to 75 the shape of the die.

In accordance with the invention, as the number of workpieces to be formed increases, the amount of discharge energy required of course increases, but not proportionally, as experiments conducted by the present inventor have disclosed. For example, the amount of energy required for formation of four workpieces at the same time in accordance with the invention is about one and a half times the amount of energy required for formation of one workpiece. This means that the machine of the invention has a very higher working efficiency than the conventional types of machines, and that the greater is the number of workpieces to be formed simultaneously, the higher the efficiency becomes.

What I claim is:

1. An electrohydraulic metal-forming machine comprising: a central discharge chamber adapted to be filled with a liquid, a plurality of dies arranged radially about said chamber in liquid communicating relation thereto and comprising two

separable die sections adapted to form a plurality of tubular chambers radially extending from said discharge chamber, each said tubular chamber enclosing a tubular workpiece therein so that said workpiece may contact said liquid at its one surface and faces said die at its opposite surface, a pair of electrodes having a gap disposed in said discharge chamber and outside said tubular chambers, and means for supplying electric energy to said electrodes to cause a spark discharge to occur between said electrodes.

- 10 2. The machine of claim 1, wherein said dies have the same shape.
3. The machine of claim 1, wherein said dies have different shapes.
4. The machine of claim 3, wherein said different shapes are 15 those into which each said workpiece is formed at different succeeding steps of a forming process.
